UNITED STATES PATENT OFFICE.

CHRISTIAN A. FREDERICKS, OF BROOKLYN, NEW YORK.

VENTILATOR.

SPECIFICATION forming part of Letters Patent No. 240,245, dated April 19, 1881.

Application filed February 3, 1881. (Model.)

To all whom it may concern:

Be it known that I, CHRISTIAN A. FREDERICKS, a citizen of the United States, residing in Brooklyn, Kings county, New York, have 5 invented certain Improvements in Ventilators, of which the following is a specification.

My invention relates to that class of ventilators in which the wind or currents of air across the top of the ventilating-shaft are relied 10 on to rotate a fan or propeller which accelerates the upward current of air in the shaft.

Heretofore ventilating devices of this general character have been variously constructed, most of them employing a propeller located in 15 the ventilating-shaft and adapted to accelerate the upward current of air in the direction of its axis, and rotated by a motor-wheel placed above the mouth of the shaft. An exhaust-fan with curved blades has also been mounted over the 20 shaft and arranged to expel the ascending current centrifugally, the rotation being effected by means of a motor-wheel connected with the fan.

My invention comprises a combined centrifugal exhaust-fan and motor-wheel, arranged entirely outside of the ventilating-shaft, adapted to be rotated by the wind, and at the same time to exhaust the air from the shaft and throw it off centrifugally.

30 I have two principal objects in view in the construction of my ventilator aside from its success in removing the foul air. One of these is to make the rotative parts as light as possible, whereby the friction and liability to get out of order are reduced to a minimum; and the 35 other is to leave the shaft as free from obstruction as possible when there is no wind and the parts are not rotating.

In the drawings, which serve to illustrate my 40 invention, Figure 1 is a vertical mid-section through a ventilator embodying my invention. Fig. 2 is a plan of the same with the cap or roof removed. Figs. 3 and 4 embody modifications, which will be more particularly referred to hereinafter.

45 Let A represent a part of a ventilating-shaft, and B a coned annulus around the top of the same. The shaft is preferably cylindrical, and the annulus may be made hollow, of sheet metal.

50 C is the cap or roof, which may be supported on standards *a a*, attached to the annulus B.

I prefer, as the best proportion, to make the radius of the outer circumference of the annulus equal to about one and two-thirds times that of the shaft, and to give its coned face an 55 angle of about forty-five degrees.

D is the fan shaft or axis, which is preferably provided with glass bearings both above and below, the lower bearing being preferably raised somewhat above the top of the shaft, as 60 shown.

To the axis D are secured the fan-blades E 65 E, which I prefer to make of some light and strong material, as papier-maché, so that they may be made very thin and have as little weight as possible. The fan-blades are so shaped at their upper and lower edges as to rotate in close proximity to the under surface of the cap and the coned surface of the annulus B, and from the axis D out to the periphery 70 of the shaft they are radial, so as to offer as little obstruction as possible to the upward current in the shaft, and produce the best centrifugal effect. Indeed, they are carried out radially, or practically so, at the top, to their 75 outer edges, but their lower acute-angled corners are curved, as at *b*, the axis of curvature being parallel to a line extending from *c* to *d* in Fig. 1. These curved extremities serve to form the motor-wheel, and as they are entirely 80 outside of or beyond the opening of the shaft, their warped surfaces will not oppose any obstruction to the upward current in the shaft, and the curved portions of the blades being almost wholly below the top of the shaft, they 85 will oppose no obstacle to the escape of the air thrown off centrifugally by the radial portions of the blades. To steady the blades I connect them together by hoops or rings *e e'*, the former secured to the lower acute-angled extremities of 90 the blades and the latter near their tops, as shown. I thus combine in one a centrifugal exhaust-fan, with radial blades arranged to receive and throw out the air freely, and a motor-wheel, arranged to be rapidly rotated by 95 the force of the wind, neither interfering with the functions of the other, and the weight of the entire structure is reduced to a minimum.

In Fig. 3 I have shown my invention as applied to those ventilating-shafts which are 100 surrounded by high buildings, where the air-currents reverberate and are sometimes down-

ward. In this construction the main shaft is divided into two branches, A', which curve inward and open face to face. The fan is arranged between the mouths, and the whole is protected 5 by a cap or roof, C. In this construction, as the currents from the branches of the shaft debouch horizontally, the axis of the fan is, of course, arranged horizontally.

In Fig. 4 I have shown a modification in 10 which the ventilator is represented in vertical mid-section and in plan. In this modification the annulus B is omitted, the under side of the cap C is coned, and the fan-blades, instead of being curved, are bent at an angle on the line c d. This construction of the cap or roof, while it lessens the effective area of the radial parts of the blades, offers a somewhat freer exit 15 for the air thrown off centrifugally.

When the fan-axis is provided with chilled- 20 metal pivots arranged to rotate in glass bearings, and the fan is properly balanced, it will be almost frictionless, and being very light, with a short axis, it will not be liable to disarrangement from the effect of high winds.

25 Having thus described my invention, I claim—

1. A ventilating-fan combining within itself 30 a wind wheel or motor and centrifugal exhaust-fan, the inner radial portions of the blades serving to exhaust the air from the shaft and discharge it centrifugally, and the outer curved or deflected parts of the blades serving to receive the force of the wind-currents and act as a motor-wheel for rotating the fan, substantially 35 as set forth.

2. A combined exhaust and motor fan hav-

ing blades constructed as shown—namely, the inner portions plain and radial from the axis to the margin of the ventilating-shaft, whereby they expose only their edges to the ascending 40 current, and the outer portions, beyond the shaft, made to extend down below the level of the top of the shaft, and that portion below the top of the shaft bent or curved to receive the force of the wind, substantially as and for 45 the purpose set forth.

3. The combination, with the ventilating-shaft, of the coned annulus around the outlet of the same, the roof or cap, and the fan having blades which extend radially from the axis 50 to the margin of the shaft-outlet, and the portions beyond the outlet arranged to drop below the mouth of the shaft and bent or curved to form a wind-motor, substantially as and for the purpose set forth.

4. In a ventilator, the combination, with a 55 ventilating-shaft having a conical annulus around its top and a cap or roof, of the fan having blades with their lower edges cut to an angle corresponding to the angle of the annulus, and arranged to droop over the same, the lower exterior angles, b, of the blades being bent or curved, as shown, and the inner part radial and plain, substantially as and for the purpose set forth.

In witness whereof I have hereunto signed my name in the presence of two subscribing witnesses.

CHRISTIAN A. FREDERICKS.
